UNITED STATES PATENT OFFICE.

ASHLEY C. BENNETT, OF MINNEAPOLIS, MINNESOTA, ASSIGNOR TO IRENE E. BENNETT, OF MINNEAPOLIS, MINNESOTA.

LIQUID-FUEL-FEEDING DEVICE.

Application filed October 16, 1919. Serial No. 330,961.

To all whom it may concern:

Be it known that I, ASHLEY C. BENNETT, a citizen of the United States, residing at Minneapolis, in the county of Hennepin and 5 State of Minnesota, have invented certain new and useful Improvements in Liquid-Fuel-Feeding Devices, of which the following is a specification.

My invention relates to liquid fuel feeding devices and an object is to provide a device of this character having a supply reservoir or tank and a suction tube through which the liquid fuel in the reservoir is fed, combined with means for maintaining a substantially constant suction head relatively 10 to the lower end of the suction tube regardless of the condition of the reservoir as it varies from a filled to a substantially empty condition. In other words, the liquid fuel 15 as it enters the suction tube is substantially under the same pressure no matter what the quantity may be that is contained in the reservoir. An instance in which my invention may be employed to advantage is found 20 in lighting plants operated by internal combustion engines in which liquid fuel contained in a supply reservoir is drawn into the carburetor by the suction of the engine. When my invention is employed the liquid 25 fuel goes into the suction tube under the same condition in regard to pressure substantially at all times and there is no necessity for changing the carburetor adjustment 30 according to the quantity of liquid fuel in the reservoir. Another object is to provide 35 a feeding device of this kind in which the liquid fuel will be confined in such manner as to avoid leakage and danger of explosions. My invention operates without the employment 40 of float feed carburetors with their well-known fire risks due to flooding.

The full objects and advantages of my invention will appear in connection with the detailed description thereof and the novel 45 features embodied in my inventive idea will be particularly pointed out in the claims.

In the accompanying drawings, which illustrate my invention in one of the embodiments which it may assume,

50 Fig. 1 is a view in vertical longitudinal section. Fig. 2 is a view in cross-section on the line 2—2 of Fig. 1 looking in the direction of the arrow.

Referring to the particular construction 55 shown in the drawings, 10 designates a

carburetor of any suitable construction connected to an internal combustion engine 12. From the lower end of the carburetor a suction tube 14 extends into a closed tank or supply reservoir 16 and terminates adjacent 60 the bottom thereof but leaving sufficient space so that the liquid fuel in the reservoir may be drawn into the tube by suction. A partition is secured within the reservoir so as to be spaced at different distances from 65 the bottom thereof for different portions of the partition. As shown, this partition includes a horizontal portion 18 and an upwardly-inclined portion 20. The suction tube 14 extends through the horizontal portion 18. An air inlet or vent tube 22 extends from the outside of the reservoir down through the inclined portion 20, terminating preferably near the highest part thereof. Provision is made for passage of air upwardly through the partition and for passage of liquid fuel downwardly through the partition. In the embodiment as shown, there is a hole 24 for passage of air upwardly and a hole 26 for passage of liquid 70 fuel downwardly through the partition into the space underneath the same. The hole 24 is located at a somewhat higher point than the hole 26. The reservoir is provided 75 at its upper side with a filling opening 80 adapted to be closed by means of an airtight closure 28.

The operation and advantages of my invention will be readily understood in connection with the foregoing description. 90 When the reservoir is first filled the liquid fuel will fill the space underneath the partition and will rise in the vent tube 22. Upon starting the engine the liquid fuel is quickly drawn out of the tube 22 and out of the space 95 underneath the inclined portion 20 of the partition. When the level in the space *s* is reduced below the hole 24 to the position shown by the dotted line *l*, air will enter the main portion of the reservoir through this 100 hole and will break the vacuum which has started to form at the top of the reservoir, with the result that liquid fuel will flow out of the opening 26 in sufficient quantity to maintain the level in space *s* substantially as indicated at *l*. The pressure head relatively 105 to the lower end of the suction tube 14 will, therefore, be substantially constant until the reservoir is nearly emptied, since the liquid fuel enters the tube 14 under a head equal 110

to the difference in height between the lower end of the tube 14 and the level indicated at 7. In this arrangement there is no chance for escape of the liquid fuel and danger of 5 explosions occurring is reduced to a minimum.

I claim:

- 10 1. A liquid fuel feeding device comprising a closed supply tank, a partition in said tank spaced from the bottom thereof at unequal distances at different portions, a suction tube extending into said tank and terminating close to the bottom thereof, and an air inlet tube connected to the space below 15 said partition, the latter being provided with means for permitting air from said space to enter the main portion of said tank and liquid fuel to pass from said main portion into said space.
- 20 2. A liquid fuel feeding device comprising a closed supply tank, a partition in said tank spaced from the bottom thereof a greater distance at one portion than at another portion, a suction tube extending into 25 said tank and terminating close to the bottom thereof, and below the portion of said partition which has a lesser spacing, and an

air inlet tube connected to the space below the portion of said partition having a greater spacing, said partition being provided with 30 means for permitting air from said space to enter the main portion of said tank and liquid fuel to pass from said main portion into the space below said partition.

3. A liquid fuel feeding device comprising a closed supply tank, a partition in said tank spaced from the bottom thereof a greater distance at one end than at the other end, a suction tube extending down into said tank and through the portion of said partition having the lesser spacing, said tube terminating close to the bottom of said tank, and an air inlet tube extending down into said tank and through the portion of said partition having the greater spacing, said air 45 inlet tube terminating at the underside of said partition, the latter being provided with holes for passage of air into the main portion of said tank and passage of liquid fuel from said main portion into the space 50 below said partition.

In testimony whereof I hereunto affix my signature.

ASHLEY C. BENNETT.
